SPRING SCALE

Application filed June 6, 1929. Serial No. 368,853.

This invention relates to spring scales, and more particularly to a novel construction for correcting the reading of the indicator for the changing length of the wire of the spring 5 and for the changes in the stiffness of the spring due to changes in temperature.

A primary object of the invention is to provide a simple, practical and reliable construction for supporting the main spring or springs 10 of the scale upon a thermostatically controlled supporting spring whereby as the material of the spring lengthens or shortens under varying temperatures, the point of support on the supporting spring will be 15 automatically shifted vertically and horizontally to increase or decrease the active length of the supporting spring to compensate for the change in length of the wire of the springs as well as the change in stiffness of the material of the springs due to changing temperature conditions. That is to say, the present invention contemplates a novel type of 20 thermostatically controlled spring suspension which as shown in drawings consists of a pair of coiled springs supported at the outer ends of flat supporting springs, supported, guided upon and movable over inclined supporting surfaces by thermostatic means, and thereby raising or depressing the 25 coiled springs to correct the zero reading of the scale and decreasing or increasing the active length of supporting flat springs and thereby compensating for the variant stiffness 30 of the springs due to temperature changes.

Other objects of the invention will appear as the description proceeds.

A preferred and practical embodiment of the invention is shown in the accompanying drawings, in which:

Figure 1 is a rear elevation of our improved construction without the surrounding scale casing.

Fig. 2 is a side elevation of the construction shown in Figure 1.

Fig. 3 is a top plan view of the hanger shown in Figs. 1 and 2 and illustrating the position and arrangement of the regulating springs.

50 Similar reference characters designate

corresponding parts throughout the several figures of the drawings.

In the embodiment of the invention shown in the drawings, the same includes a frame F having the hanger portion 1 at the upper end thereof and offset as indicated at 2 to accommodate the main springs S and their associated mechanism. As usual, the main springs S are connected at their lower ends with the runner R which carries the pan or other load supporting element of the scale.

As previously indicated, one of the distinctive features of the invention resides in the provision of a novel support for the main springs S. To that end the said springs are connected at their upper ends to suitable links 3 which are carried on the pivot pins 4 mounted in eyes 5 at the outer ends of the supporting and compensating springs 6. These springs rest upon the inclined surfaces 7-a of the locking members 7, which prevent the springs from sliding down their inclined seats when the scale is under load. Their upper surfaces bear against the inclined surfaces 8 of the bracket members 9 pivoted at 10 to the upper end of the frame F at opposite sides of the opening 11 therein. The bracket member and the inclination of the seat may be regulated by means of the slot 12, bolt 13 and nut 14. The locking members 7 are pivoted to the bracket members 9 at 7^b. The inner ends of the supporting and compensating springs 6 are connected by suitable clamps 15 on the studs 16 which are adjustably secured in the upper ends of the thermostats TT by means of the nuts 17, 18. The thermostats TT are secured in adjusting blocks 19 which are adjustably secured to the frame F by means of the slots 20, bolts 21 and nuts 22. By raising or lowering the adjusting blocks 19 the active length of the thermostats TT may be increased or diminished. The thermostats TT may be constructed of any suitable metals but in the embodiment shown preferably consists of an inner layer or strip 23 of iron or steel and an outer layer or strip 23a of brass or other material having a relatively high coefficient of expansion as compared with the material of the layer 23.

100

Thus when the thermostats are subjected to changing temperature conditions the upper ends thereof will be moved toward and from each other and move the supporting springs 6 on the inclined seats or surfaces 7-a, the inward movement elevating the ends and diminishing the active lengths of such springs and the outward movement lowering the supporting ends and increasing their active length and thereby varying the position of the supporting ends of said springs and their stiffness.

When the temperature rises the springs are drawn toward each other and the rise of the ends of the springs corresponds with the increased length of the main springs and causes the pointer to register with zero and the shortening and stiffening of these springs compensates for the decrease in stiffness of the main springs due to increase in temperature. When the temperature falls, the springs are moved outward and their ends depressed and flexibility increased. The depression of the ends corresponds with the decrease of length of the main springs and causes the indicator to register with zero and increased flexibility of the supporting springs compensates for the increased stiffness of the main springs causing the indicator to correctly register the weight on the scale under all loads and temperature changes and likewise to maintain the indicator at zero when the scale is not under load under all changes in temperature. When the spring is under no load, the locking members 7 freely permit the thermostats TT to move the supporting springs 6 on the inclined seats 7-a, and when the scale is under load, the locking members 7 tilt slightly and force the springs 6 against the inclined surfaces 8 and prevent them from sliding on their inclined seats.

The runner R has pivotally connected thereto a rack 24 which meshes with the pinion 25 on the indicator shaft 26 on the outer end of which the indicator 27 is mounted. This indicator 27 cooperates with a suitably calibrated dial 28 in the usual manner. In connection with the rack 24 it is pointed out that the same may be of any suitable material, as previously indicated, since all of the desired corrections and compensations for changes in the spring material due to changes in temperature are taken care of by the novel arrangement of the springs and their support and actuation by the thermostat.

It is apparent that one or any number of load and supporting springs may be used.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

We claim:—

1. In a spring scale the combination with a main load responsive spring, of a thermostat and a shiftable support for said spring connected to said thermostat and adapted to compensate for the change in length of the wire of the spring and the changes in the stiffness thereof due to changes in temperature. 70

2. In a spring scale the combination with a main load responsive spring, of a thermostat and a resilient support for said spring directly connected to said thermostat and adapted to compensate for the change in length of the wire of the spring and the changes in the stiffness thereof due to changes in temperature. 75

80 3. In a spring scale the combination with a main load responsive spring, of a thermostat, a spring supporting said load responsive spring connected at one end to said thermostat and at its opposite end to said load supporting spring, an inclined seat for said flat spring and means for holding said spring in contact with said seat, whereby the movement of the spring over the seat will compensate for the change in length of the wire of the spring and the changes in the stiffness thereof due to changes in temperature. 85

90 4. In a spring scale the combination with a main load responsive spring, of a thermostatically controlled spring supporting at its outer end said load responsive spring, and a combined guiding and supporting seat for said spring, whereby the movement of said spring over said seat will compensate for the change in length of the wire of the spring and the changes in the stiffness thereof due to changes in temperature. 95 100

105 5. In a spring scale the combination with a main load responsive spring, of a thermostatically controlled spring supporting at its outer end said load responsive spring, and a combined guiding and supporting seat, said seat being inclined from the horizontal and adapted to support the said flat spring whereby the movement of said spring over said seat will compensate for the change in length of the wire of the spring and the changes in the stiffness thereof due to changes in temperature. 110 115

120 6. In a spring scale the combination of a main load responsive spring, of a resilient member operatively connected at one end with said spring, an inclined seat for supporting said resilient member, and a thermostat connected to the end of said resilient member opposite the connection of the load responsive spring therewith.

125 7. In a spring scale the combination with a main load responsive spring, of a resilient member, an inclined seat for supporting said resilient member, a link connecting the outer end of said resilient member with the load responsive spring and a thermostat connected with the inner end of said resilient member. 130

8. In a spring scale the combination of a main load spring, a supporting spring on the free end of which the main spring is supported, an inclined seat for said supporting spring, and thermostatic means for moving said supporting spring longitudinally on its seat.

9. In a spring scale the combination of a main load spring, a supporting spring on the free end of which the main spring is supported, an inclined seat for said supporting spring, means for guiding and holding the supporting spring on its inclined seat, and thermostatic means for moving said supporting spring longitudinally on its seat.

10. In a spring scale the combination of a main load spring, a supporting flat spring on the free end of which the main spring is supported, said supporting spring being supported on an inclined seat, and thermostatic means for moving said supporting spring longitudinally on its seat.

11. In a spring scale the combination of a main load spring, a supporting spring on the free end of which the main spring is supported, said supporting spring being supported on an inclined seat, and thermostatic means for moving said supporting spring longitudinally on its seat, the supporting spring, its inclined seat and said thermostatic means cooperating with the main load spring and indicator to compensate for changes of length of the springs and changes in the stiffness of the springs due to temperature changes.

12. In a spring scale the combination of a main load spring, a supporting spring on the free end of which the main spring is supported, said supporting spring being supported on an inclined seat, means for adjusting the inclination of said seat, and thermostatic means for moving said supporting spring longitudinally on its seat.

13. In a spring scale the combination of a main load spring, a supporting spring on the free end of which the main spring is supported, an inclined seat for said supporting spring, thermostatic means for moving said supporting spring longitudinally on its seat and automatic means for locking said supporting spring against longitudinal movement when the scale is under load.

14. In a spring scale the combination of a main load spring, a supporting spring on the free end of which the main spring is supported, an inclined seat for said supporting spring, thermostatic means for moving said supporting spring longitudinally on its seat and means for regulating the activity of the thermostatic means.

15. In a spring scale the combination of a main load spring, a supporting spring on the free end of which the main spring is supported, an inclined seat for said supporting spring, thermostatic means for moving said supporting spring longitudinally on its seat

and means for manually adjusting the position of said supporting spring on its seat.

Signed at New York city, in the county of New York and State of New York, this 29th day of May, A. D. 1929.
